UNITED STATES PATENT OFFICE.

GEORGE C. ROPPERT, OF MILWAUKEE, WISCONSIN, ASSIGNOR OF ONE-THIRD TO
JOSEPH J. LIBERATORE, OF MILWAUKEE, WISCONSIN.

MEANS FOR ATTACHING RUBBER HEELS AND TREADS TO SHOES.

Application filed August 29, 1925. Serial No. 53,326.

This invention relates to method and means of attaching a rubber heel to a shoe. In attaching rubber heels to shoes, it has been found the universal practice, prior to this invention, to nail the heels to the shoe. This results in discomfort to the wearer and also frequently in detaching of the heel from the shoe. For instance, as soon as there is any material wear, the rubber thickness is reduced and the weight is imposed upon the heads of the nails, frequently driving them through the soles of the shoes to the discomfort of the wearer. In addition to this, the continued pounding or movement of the rubber works the nails loose with a consequent detaching of the heels.

Prior to this invention, it has been considered wholly impossible to cement rubber heels to the shoes without the use of nails, and the manufacturers have considered this, as stated, wholly impractical and also impossible. However, I have found that rubber heels may be cemented to shoes without employing any nails for attaching them in such a manner that they will remain attached to the shoe even beyond the life of the shoe.

Objects of this invention are therefore to provide a method and means of attaching rubber heels to shoes without the use of nails, and to provide a simple and extremely strong and reliable method of attaching the rubber heels to the shoes by the use of cement so that the rubber heels will remain attached to the shoes even beyond the life of the shoes, and will neither become loosened nor cause any discomfort whatsoever to the wearer, even after prolonged use.

Further objects are to provide a method and means of attaching rubber heels to shoes, which may be employed by an unskilled laborer with assurance that a permanent union is always attained and without the use of any nails whatsoever.

An embodiment of the invention is shown in the accompanying drawings, in which:

Figure 1 is a bottom view of the heel portion of a shoe, with the rubber heel attached and with parts broken away for clearness.

Figure 2 is a side elevation of the structure shown in Figure 1, such view being partly in section.

Figure 3 is a very much enlarged, sectional view showing the parts in one stage of the process of attaching the heel.

Figure 4 shows the same parts in their final position after attachment has been effected, such view being also a very much enlarged section of a fragment of the shoe.

Referring to the drawings, particularly Figures 1 and 2, it will be seen that the shoe 1 has a binder 2 attached to its heel portion 3 by means of a line of stitching 4 which extends around the marginal edges of the binder and which may extend through other portions in addition to the marginal edges if desired. Preferably, in attaching the binder it is cemented to the heel portion of the shoe to hold it flat and to attach it, and it is thereafter stitched in place. After the binder has been positioned, its lower face is coated with cement, preferably in a hot condition, and the upper face of the rubber heel 5 is also similarly coated. While the cement is still soft, the rubber heel is pressed tightly against the binder to insure an intermeshing of the parts of the heel and the adjacent portions of the binder, and this pressure is preferably maintained while the cement is hardening.

Referring to Figure 2, it is to be noted that the binder is shown very much exaggerated in this view for the sake of clearness, although it is to be understood that the binder is a thin sheet of pliable material.

At this point it is to be particularly noted that the preferable manner of attaching the heel is through the use of a thin piece of upper leather used as the binder, with the flesh side of the leather presented downwardly. In this connection, Figures 3 and 4 are called to attention and it will be seen that these figures disclose the microscopic nature of the binder. For example, in Figure 3 a fragment only has been shown, and it will be seen that the binder has a multitude of microscopic teeth 6 on its flesh side, which project downwardly. Further, it is noted that the rubber heel 5 is porous and the pores of its upper side cooperate with the microscopic teeth of the binder. The cement joining the binder to the shoe is indicated

at 8, and it is to be noted that the stitching passing through the binder and the heel portion of the shoe is not shown, as it would be so large in proportion to the thickness of 5 the binder as to interfere with the proper showing. Therefore, Figures 3 and 4 are to be understood as sections through the portions of the shoe and heel remote from the stitching.

10 After the binder has been securely attached to the heel of the shoe, its lower flesh face and the upper face of the heel are coated with cement preferably while the cement is hot. Thereafter, the heel is pressed tightly 15 against the coated flesh side of the binder with the result that the minute fingers 6 of the binder extend into the pores of the rubber heel, as shown in Figure 4, and are very tightly cemented and intermeshed with 20 this portion of the rubber heel. The cemented joining of the flesh side of the binder to the rubber heel is indicated at 9 in Figure 4.

In actual tests conducted in accordance 25 with the disclosure of this invention, it has been found that a binder employed in the manner described retains the rubber heel to the shoe throughout the entire life of the shoe, without any detaching of any edge or 30 portion whatsoever of the heel from the binder. In other words, the test was conclusive of the fact that this invention has been actually tried in practice and found eminently satisfactory.

35 Although the invention has been de-

scribed in considerable detail, it is to be understood that the invention may be variously embodied, and is therefore, to be limited only as claimed.

I claim:—

1. The combination of a shoe, a binder of leather secured to said shoe at the bottom thereof with the flesh side of the leather down, and a rubber tread cemented to the flesh side of the binder.

2. The combination of a shoe, a thin pliable binder secured to said shoe at the heel portion, said binder having a multitude of minute fingers projecting downwardly, and a rubber heel having its upper surface cemented to said binder, whereby the minute fingers of said binder project into the pores of the rubber and are cemented thereto.

3. The combination of a shoe, a leather binder stitched to the heel portion of the 55 shoe with the flesh side of the binder down, and a rubber heel cemented to the flesh side of the binder.

4. The combination of a shoe, a binder of thin upper leather cemented and stitched to 60 the heel portion of the shoe with the flesh side of the binder down, and a rubber heel cemented and pressed to the flesh side of said binder.

In testimony that I claim the foregoing I 65 have hereunto set my hand at Milwaukee, in the county of Milwaukee and State of Wisconsin.

GEORGE C. ROPPERT.
